UNITED STATES PATENT OFFICE.

WILLIAM H. TAYLOR, CHARLES W. DOWNS, AND JACOB W. BARBEY, OF DETROIT, MICHIGAN.

MULTIPLE-FUSE PLUG.

Application filed March 10, 1921. Serial No. 451,298.

To all whom it may concern:

Be it known that we, WILLIAM H. TAYLOR, a subject of the King of Great Britain, and CHARLES W. DOWNS and JACOB W. BARBEY, 5 citizens of the United States, residing at Detroit, county of Wayne, State of Michigan, have invented a certain new and useful Improvement in Multiple-Fuse Plugs, and declare the following to be a full, clear, and 10 exact description of the same, such as will enable others skilled in the art to which it pertains to make and use the same, reference being had to the accompanying drawings, which form a part of this specification.

15 This invention relates to multiple fuse plugs and the principal object of the invention is to provide a fuse plug having a series 20 of fuse elements therein, means being provided for connecting one of the elements at a time in the circuit, the said means including indicating means to indicate which fuse element is connected. With the fuse plugs now commonly in use containing a single fuse element, when the fuse element is blown 25 it is necessary to discard the entire fuse plug as being unfit for further use and therefore one of the main objects of the invention is to provide a fuse plug which may be blown a number of times before being discarded. 30 A further object of the invention is to provide a fuse plug of the character described provided with means for separately indicating which fuse elements are blown and which are not blown. A novel feature of 35 the invention resides in the provision of means for indicating which fuse element is in the circuit in combination with means for indicating whether or not the said fuse element is blown, said indicating means also 40 indicating the fuse elements which are not blown so that the user may easily change the contact from a blown fuse element to one which is not blown. A further object of the invention is to provide a multiple fuse plug 45 which is very simple and efficient in operation and in which the change from one fuse to the other within the plug may be very easily accomplished. These objects and the several novel features of the invention are 50 hereinafter more fully described and claimed and the preferred form of construction by which these objects are attained is shown in the accompanying drawings in which—

Fig. 1 is a plan view of a fuse plug embodying my invention with the mica cover

partly broken away to show the construction.

Fig. 2 is a section taken on line 2—2 of Fig. 1.

Fig. 3 is a view of the under side of the 60 fuse plug.

Fig. 4 is a detail view of the contact pin for the different fuse elements.

Fig. 5 is a perspective view of one of the 65 fuse elements.

The fuse plug consists of a body 1 having a series of vent chambers 2 therein the said chambers widening out at the upper end to provide rectangular openings 3 in the upper face of the plug as shown in Fig. 1. A recess 5 is provided in the central portion 4 of the fuse plug and an aperture 6 extends through the portion 4 of the fuse plug and opens into the recess 5. A shallow recess is provided in the upper face of the plug having a flange 7 thereabout and in this recess is inserted a mica disc 8 which is held in place by the flange 7 as will be readily understood. As shown in Fig. 1 the disc 8 covers all but a small portion of the rectangular openings 3 80 and also completely covers the recess 5 as shown in Fig. 2. The lower end of the plug which is of smaller diameter carries an outer shell 9 which is formed of copper, brass or other good conducting metal and 85 which is formed with threads 10 therein adapted to fit the threads of a socket. Secured to the outer shell 9 is a series of fuse elements 11 shown more particularly in Fig. 5 which are preferably soldered to the shell 90 9 in order to make a good contact. These fuse elements 11 are each provided with an angularly extending end 12 adapted to fit in the upper end of a series of recesses 13 provided therefor and spaced circumferentially 95 about the aperture 6 as shown more particularly in Figs. 2 and 3. Each fuse element 11 is provided with an aperture 14 therein as shown more particularly in Fig. 5 and by varying the size of the aperture 100 the current carrying capacity of the fuse element is varied. When the fuse elements 11 have been secured in position the apertures 14 and portions adjacent thereto are positioned in the vent chambers 2 of the fuse 105 plug as shown in Fig. 2. To hold the fuse elements in position I provide a portion 15 made of a plastic insulating material which is adapted to harden and which is provided with points 16 extending between the aper-

110

tures 13 providing guides for the bent end 17 of a contact pin 18 which is provided with a return bent end 19 adapted to fit the recesses 13. This pin 18, as shown in Fig. 4, is provided with an upwardly extending point 20 and in assembly the portion 18 of the pin is inserted through the aperture 6 at which time the point 20 is bent over in the recess 5 as shown in Fig. 2 and the mica disc is then inserted in the recess therefor.

In operation the contact pin 18 is positioned within the fuse plug as shown in Fig. 2 and, as will be noted from Fig. 1, the point 20 thereof indicates the fuse element 15 which is contacted. The pin 18 is of practically the same diameter as the aperture 6 and therefore tends to bind slightly in the said aperture thus preventing the member 18 from dropping down in the said aperture and withdrawing the end 19 from the recess therefor. When the contact pin has been set, as shown in Fig. 2, the fuse plug is threaded into a socket therefor, the 20 depending bent end 17 engaging the contact point in the said socket which forces upwardly on the pin 18 and holds the return bent end 19 thereof in contact with the angularly bent end 12 of the respective fuse element 11. While thus assembled should 25 too great a current pass through the fuse element 11 the element will blow adjacent the aperture 14 where the member 11 is of the least current carrying capacity and the force of the fuse blowing will be directed 30 upwardly through the vent chamber 2 and opening 3, the force of the blow tending to pass outwardly through the opening 3 adjacent the edge of the mica disc 8 which discolors the same over the aperture 2 and indicates that the fuse is blown. When this 35 occurs the fuse plug is removed from the socket and the bent end 17 of the pin 18 is drawn downwardly until limited by the point 20 striking the bottom of the recess 40 45 5. At this time the return bent end 19 is clear of the fuse plug and the contact pin 18 may be turned to position the return bent end 19 thereof in another aperture 13 which connects with a fuse element which 50 55 60 65 70 has not been blown as indicated by the mica being clear and transparent over the opening 3 for the respective fuse element. It can thus be seen that each time the fuse blows the contact pin may be reset to contact a fuse element which has not blown as indicated by the mica being clear and transparent over the said unblown fuse element and the device may be thus reset several times before the plug is entirely 75 80 85 90 95 100 105 110 115 120 125 130 used up. While we have shown six different fuse elements in the drawing it is to be understood that a greater or less number may be utilized as desired or as found most efficient in operation. A coiled spring 21 shown in dotted lines in Fig. 2 is prefer-

ably utilized on the pin 18 to hold the end 19 in contact with the respective fuse element. This spring 21 holds the pin 18 in position and prevents accidental displacement thereof.

From the foregoing description it becomes evident that the device is very simple and efficient in operation, of comparatively low manufacturing cost and provides a fuse plug which may be used many times before being discarded and which accomplishes the objects described.

Having thus fully described my invention, its utility and mode of operation, what I claim and desire to secure by Letters Patent of the United States is—

1. A multiple fuse plug comprising a body formed of insulating material having a central aperture therethrough and a series of recesses spaced circumferentially about the said aperture, an outer contact shell threaded to fit a socket, a series of fuse elements connected thereto, each provided with an angularly bent end extending into a recess, a contact pin rotatably mounted in the central aperture and having a return bent end adapted to contact any fuse element, and an indicator carried by the said pin observable from the outer end of the plug indicating the fuse element contacted thereby.

2. In a fuse plug, a body of insulating material having a longitudinal central aperture, an outer shell of metal adapted for threaded relation with a socket providing an outer contact member, a series of fuse elements in spaced relation connected with the said shell and extending inwardly toward the central aperture, a central contact pin actuatable from the contact end to position in contact with the end of any of the fuse elements, the contact pin being held in fixed relation with the element upon insertion of the plug in the socket, and an indicator member on the pin observable from the exterior of the plug when in use indicating the element through which the circuit is made.

3. In a fuse plug, a hollow body of insulating material, a transparent member therefor, an outer contact member on the body adapted for threaded relation with a socket, a series of fuse elements in spaced relation extending toward the center of the body and connected with the outer contact member, a central contact pin adapted to be placed in contact with any one of the fuse elements and locked from displacement by insertion of the plug in the socket, a series of vent chambers, one for each fuse element across the lower end of which the fuse element extends in each instance, said chambers extending to the outer exposed end of the plug, the vent chambers each opening to atmosphere at the edge of the transparent member whereby the blowing of any fuse

tends to discolor the same at the edge, and an indicator member observable from the outer end of the plug indicating the element in contact with the pin.

5 4. In a fuse plug, a body having a central longitudinal aperture, an outer metal contact member adapting the plug for threaded connection with a socket, a series of fuse elements at the inner end of the plug connected with the said outer contact member and extending in spaced relation radially toward the center of the plug, a series of longitudinal recesses about the central aperture at the inner end in each of which a 15 fuse element terminates, a central contact pin having a return bent lower end adapted for insertion in any one of the longitudinal recesses, the opposite end of the pin having means thereon showing the side of the 20 pin on which the lower return-bent end is positioned, a series of vent chambers one for each fuse element closed at the lower end and open to atmosphere through the outer end, a mica cover for the outer end of 25 the plug covering the major portion of the said chambers, each element having a portion of least current carrying capacity positioned in the respective vent chamber.

5. A multiple fuse plug comprising a 30 body formed of insulating material having a central aperture therethrough and a series of recesses spaced circumferentially thereabout, the said body being also provided with a series of vent chambers, an outer contact shell threaded to fit a socket, a series of 35 fuse elements connected thereto each extending through a vent chamber and into a recess, the point of least current capacity of the fuse elements being positioned in the 40 said vent chambers, a mica disc covering the vent chambers at the outer end of the plug and adapted to be discolored adjacent the vent chamber when the respective fuse element is blown thereby providing an indicator, a contact pin adapted to contact the 45 end of any fuse element, and an indicator carried by the said pin indicating the fuse element contacted thereby and in combination with the mica disc indicating whether 50 the fuse element contacted is blown.

6. A multiple fuse plug comprising a body formed of insulating material having a central aperture therethrough and a series of recesses circumferentially thereabout, the 55 said body being also provided with a series of vent chambers, an outer contact shell threaded to fit a socket, a series of fuse elements connected thereto each extending through a vent chamber and into a recess, 60 a mica disc providing a cover for the vent chambers, a contact pin rotatably mounted in the central aperture having a return bent

end adapted to contact the end of any fuse element, and an indicator carried by the said pin observable through the mica disk indicating the fuse element contacted thereby.

7. In a fuse plug, a body of insulating material having a central aperture and an enlarged recess at the outer end, a metal shell on the inner end of the plug adapted for threaded relation with a socket and providing an outer contact member, a series of fuse elements in spaced relation extending radially inward toward the center of the plug, a series of vent chambers one for each fuse element closed at the inner end and opening to atmosphere through an outer end of the plug, a transparent plate covering the major portion of said chambers at the outer end and the central recess, a central contact pin in the said central aperture of the plug having a return bent lower end, the lower end of the plug having a series of longitudinal recesses in which the inner end of each fuse element is positioned, said return bent end being adapted for insertion in any one of the longitudinal recesses, the said pin at the outer end having a portion bent outwardly on the same side as the opposite return bent end and being observable through the said transparent member and indicating from the exterior the position of the inner return bent end.

8. In a fuse plug, a body of insulating material, an outer contact member secured to the lower end thereof, a series of fuse elements extending in spaced relation from the outer contact member toward the center of the body, a central contact member movable longitudinally in the body and having an end adapted to be positioned in contact with any one of the fuse elements, the opposite end of the said central member having a pointer thereon observable from the outer end of the body and indicating the fuse element in circuit.

9. In a multiple fuse plug, a body having a central aperture and a series of recesses spaced circumferentially about the said central aperture, an outer contact member, a series of fuse elements connected thereto each extending into a recess, and a contact pin carried in the central aperture having a return bent end adapted to be inserted in any recess to contact the fuse extending thereinto, the opposite end of the pin having an indicator extending on the same side of the pin as the said return bent portion of the opposite end.

In testimony whereof, we sign this specification.

WILLIAM H. TAYLOR.
